RAILWAY TRAFFIC CONTROLLING APPARATUS

Ronald A. McCann, Swissvale, Pa., assignor to
The Union Switch & Signal Company, Swiss-
vale, Pa., a corporation of Pennsylvania

Application March 14, 1934, Serial No. 715,527

9 Claims. (Cl. 246—3)

My invention relates to railway traffic controlling apparatus, and in particular, to apparatus of the type employing a movable control member for the remote control of a movable device such as a railway switch in which the operation of the device under unfavorable conditions is prevented by electrical locking means.

One feature of my invention resides in the provision of means for preventing an operation of the device in response to a movement of the control member unless the locking is released at the time that the member is moved. My apparatus is so arranged that if the control member is moved while the locking is effective, the device does not move automatically to a position corresponding to that of the member when the locking becomes released, and that to effect a movement of the device under this circumstance when the member and the device are not in corresponding positions, the member must be moved away from and then back to the position corresponding to that to which it is desired to move the device. In respect to this feature, my invention is an improvement upon that disclosed in a copending application, Serial No. 695,294, filed October 26, 1933, by Earl M. Allen and Howard A. Thompson, for Interlocking control apparatus. My invention is also an improvement over that disclosed in a patent granted to Charles A. Brooks, Patent No. 2,007,635, issued July 9, 1935, for Railway switch controlling apparatus.

I will describe four forms of apparatus embodying my invention as applied to the remote control of a power operated railway track switch governed by a manually operable control lever, and will then point out the novel features thereof in claims.

In the accompanying drawing, Fig. 1 illustrates diagrammatically one form of my invention. Fig. 2 illustrates an alternative arrangement employing a different type of control lever. Fig. 3 illustrates an arrangement of apparatus embodying my invention which is particularly adapted for use when the switch is at a considerable distance from the control lever. Fig. 4 illustrates an alternative form employing a centrally biased three-position control lever.

Similar reference characters refer to similar parts in each of the views.

Referring to Fig. 1, the reference L designates a control member comprising a manually operable lever having contacts closed in the normal and reverse positions, as indicated by the references n, n¹ and r, r¹, respectively, and other con-

tacts closed in intermediate positions, as indicated by the references b, b¹ and d, d¹, respectively. The drawing includes a single line diagram representing the rails of a section of track including a power-operated track switch S having an operating mechanism W controlled by lever L. Associated with lever L is a polarized storing relay P which, as here shown, is of the permanent magnet stick type. Relay P is arranged to be energized by a momentary impulse of current as the lever L is moved through an intermediate position under conditions favorable for the operation of the track switch, and is adapted to move its contact l in one direction or the other in accordance with the relative polarity of the impulse and to maintain the contact in its last operated position when deenergized. The operating mechanism W for the track switch as illustrated is of the motor operated type, and is controlled by a polarized control relay WR having a control circuit including the contacts of relay P and of lever L and of a locking relay LR. The detailed circuits for the control of relay LR have been omitted in order to simplify the drawing, but it is to be understood that in accordance with the usual practice, relay LR is energized only when conditions are favorable for the operation of the switch by closing a circuit which as indicated in the drawing, includes a front contact of a detector track relay TR for the track section containing the switch and front contacts of approach or section locking relays ES and WS governed by traffic approaching the switch. Relay TR is controlled by the usual detector track circuit and becomes released to deenergize relay LR when the section containing switch S is occupied by a train. Relays ES and WS provide means for deenergizing relay LR when a train is approaching the switch section and may be controlled in various ways by means well known in the art. For example, these relays may be provided with control circuits arranged like those of the approach locking relays U¹ and U² disclosed in the Allen & Brooks Patent No. 1,929,047, issued Oct. 3, 1933, for Remote control apparatus.

The control circuit for relay WR may be traced from one terminal B of a suitable source of energy, normal contact n of lever L, normal or left-hand contact l of relay P, contact 2 of relay LR, wire 3, relay WR, wire 4, contact 5 of relay LR, contact n¹ of lever L to the other terminal C of the same source of energy. When this circuit is closed, relay WR will be energized in the normal direction as shown. Assume now that the oper-

ator moves lever L to the right, while locking relay LR is energized. As the lever passes the position to close contact b, relay P will be momentarily energized in such a direction as to maintain its contact closed in the last operated position, over a circuit which may be traced from terminal B, contact b of lever L, relay P, contact 6 of relay LR, contact b¹ of lever L to terminal C. Continued movement of the lever will cause contact d to be closed to complete a circuit for energizing relay P in the reverse direction to move its contact 1 to the right, this circuit being similar to that just described except that it includes contacts d and d¹, as is obvious from the drawing. When the movement of lever L to its full reverse position is completed, a circuit will be closed from terminal B, reverse contact r of lever L, contact 5 of relay LR, wire 4, relay WR, wire 3, contact 2, of relay LR, right-hand contact 1 of relay P, contact r¹ of lever L to terminal C. Relay WR will therefore be energized in the reverse direction and the reverse operating circuit for the switch motor will become closed. The switch operating circuit may be traced from terminal B, front contact 7 and reverse polar contact 8 of relay WR, armature 9 of the switch motor, reverse polar contact 10 of relay WR, switch circuit controller 11 controlled by the switch, field winding 12 of the switch motor to terminal C. When this circuit is closed, the motor will be energized to operate the switch to its reverse position, the motor circuit being opened by contact 11 when the switch completes its stroke.

If now lever L is returned to its normal position, while relay LR is energized, the above described operations will occur in the reverse order. Relay P is momentarily energized to its last operated position when contacts d and d¹ close, and to a position to move its contact 1 to the left when contacts b and b¹ close, and when L reaches its normal position, relay WR will be energized in its normal direction. The circuit for the switch motor will then be completed over the normal polar contacts 8 and 10 of relay WR to cause the switch to move to normal, the switch motor circuit being opened at the completion of its operation by means of contact 13, which in this instance is included in the motor operating circuit instead of contact 11.

If now lever L is moved to its full reverse position while locking relay LR is deenergized, it is evident that neither relay P nor relay WR will respond and that when the locking is released so that relay LR again becomes energized, relay P will remain deenergized as long as lever L remains reversed in the position to close contacts r, r¹, and therefore contact 1 will remain closed to the left, so that the circuit over contact r¹ will be open and relay WR will remain deenergized. In order to now reverse relay WR, lever L must be moved away from its reverse position, not necessarily to normal but at least far enough to close contacts d, d¹, and must then be moved again to its reverse position to close contacts r, r¹. If, however, the operator moves lever L to the intermediate position while relay LR is deenergized to close contacts d, d¹, relay P will become energized automatically to close contact 1 to the right when relay LP picks up, but in this case no operation of relay WR will ensue because lever L is so arranged that contacts d, d¹ and r, r¹ can not be closed at the same time. Relay WR can, however, in this instance be reversed by merely operating lever L from the intermediate position to its full reverse position. Since the circuits

controlled by lever L are symmetrical with respect to the normal and reverse positions and also with respect to the corresponding intermediate positions, it is evident that the conditions governing the control of relay WR from reverse to normal are similar to those above described in connection with its control from normal to reverse. It follows, therefore, that any operation of lever L made while the switch locking is effective is without result, and that to control the switch after such operation, lever L must again be operated after the locking has become released.

Certain types of switch control levers employed in practice are so arranged that it is not convenient to equip them with intermediate contacts such as b and d, and when such levers are used, the arrangement shown in Fig. 2 may be employed, in which the lever L is provided with a single contact c closed at mid-stroke in addition to the usual normal and reverse contacts. In Fig. 2, I employ a double battery arrangement for controlling the polarized relay WR, that is, in addition to the battery having terminals B and C, I provide a second battery of opposite polarity as indicated by the terminals N and C. In Fig. 2, the normal circuit for relay WR may be traced from terminal B, contact n of lever L, right-hand contact 1 of relay P, contact 2 of relay LR, wire 3, relay WR to the other terminal C of the same source of energy. If lever L is reversed while relay LR is energized, a circuit will be closed momentarily at mid-stroke, which may be traced from terminal B, contact c, slow release relay M to terminal C, so that relay M will pick up and remain energized for a short time after contact r is closed, to effect the momentary closing of a circuit from terminal B, contact r of lever L, relay P, contact 14 of relay M, contact 6 of relay LR to terminal C. Relay P will be energized over this circuit in such a direction as to close its left-hand contact whereupon a circuit will be closed from terminal N of the second source of energy, contacts r¹, 1, and 2, wire 3, relay WR to the other terminal C of the same source of energy, to energize relay WR in the reverse direction to cause the switch to be reversed as already described. If now lever L is restored while relay LR is energized, it is clear that relay M will again be momentarily energized, and that when contact n of lever L is closed relay P will be energized by current from source N to close its right-hand contact to establish the normal circuit for relay WR. In Fig. 2, just as in Fig. 1, it is clear that the switch control circuit including relay WR is not closed unless relay P and lever L occupy corresponding positions and that relay P is not operated unless relay LR is energized, and therefore, a movement of lever L while relay LR is deenergized is without effect.

The arrangement of my apparatus illustrated in Fig. 3 is adapted for use when the switch is at a considerable distance from the lever, as would be the case, for example, when my invention is used in connection with a centralized traffic control system. In this case, the locking relay LR would be located adjacent the switch and its condition would be made manifest to the operator by means of a slow release repeating relay LP connected in series in the control circuit for the switch. In this form of my invention, my control lever L has merely the usual normal and reverse contacts but no intermediate contacts. Referring now to Fig. 3, the normal control circuit for relay WR may be traced from terminal B, contact n of

lever L, reverse contact 1 of relay P, relay LP, line wire 3, contact 2 of relay LR, relay WR to the other terminal C of the same source. If, now, lever L is reversed, the circuit for relays LP and WR will be opened but relay LP being a slow release relay will remain in its picked up position for a time sufficient to permit a circuit to be closed momentarily from terminal B, contact r of lever L, relay P, contact 15 of relay LP to terminal C. Relay P will, therefore, become energized in its normal direction to complete the reverse control circuit from terminal N, contact r¹ of lever L, left-hand contact 1 of relay P, the winding of relay LP, wire 3, contact 2 of relay LR, relay WR to terminal C of the same source. In Fig. 3 it will be noted that relay P remains energized in one direction or the other as long as relay LR remains energized, but it becomes deenergized due to the release of relay LP when the locking is effective. If, now, lever L is moved out of correspondence with relay P while the locking is effective and relay LP deenergized, it is clear that when relay LR again picks up no circuit will be available for picking up LP and, therefore, relay P will not become energized to move its contact into correspondence with the lever, but, on the other hand, the lever must be moved so as to bring it into correspondence with relay P in order to pick up relay LP and to permit the switch to be operated.

The form of my invention illustrated in Fig. 4 employs a centrally biased three-position lever which may be moved to momentarily close its left-hand or right-hand contacts n or r to operate the switch, but which when released returns automatically to its middle position in which contacts c and c¹ are closed. As will be clear from the drawing, the normal control circuit for relay WR includes contact c of lever L, and the left-hand contact 1 of relay P, but this circuit does not open when lever L is operated to momentarily close contact r to energize relay P in the reverse direction, therefore relay LP is maintained energized after the lever is operated until relay P reverses. If lever L is then released, the reverse control circuit for relay WR from terminal N and including contact c¹ and right-hand contact 1 will then become closed. Relay LP, therefore, as employed in the arrangement of Fig. 4, does not need to be a slow release relay, and, furthermore, the polarity of the current supplied to the control circuit for relay WR depends solely upon the position of relay P and not upon the position of the lever, in this form of my apparatus. It is clear, however, that relay P can be operated only during the time that the locking is released and relay LP is energized, and that in common with that of the other views, the apparatus of Fig. 4 operates in such a manner that any operation of lever L while the locking is effective is devoid of result. For example, if lever L is reversed while relay LP is deenergized and held reversed until relay LP picks up, relay P will then become reversed but the reverse control circuit will be open at contact c¹ and relay WR will not be operated until lever L is returned to its middle position. If lever L is returned to its middle position before relay LP picks up, no reversal of relay P will occur, and therefore in either case, the operation of the lever while relay LP is released is without effect.

Although I have herein shown and described but four forms of apparatus embodying my invention, it is understood that various changes and modifications may be made therein within

the scope of the appended claims without departing from the spirit and scope of my invention.

Having thus described my invention, what I claim is:

1. In combination with a railway track switch, a locking relay controlled by traffic conditions adjacent the switch, a two-position control lever, a two-position relay adapted when deenergized to remain in its last operated position, a control circuit for said relay closed momentarily as the lever is moved from one position to the other for operating the relay to a position corresponding to that which the lever is moved, a control circuit for the switch controlled in accordance with the position of said two-position relay and including a front contact of said locking relay, and means for preventing the operation of said two-position relay unless the movement of the control lever occurs when the locking relay is energized.

2. In combination with a railway track switch, a polarized control relay for the switch, a locking relay for indicating when traffic conditions are favorable for operating the switch, a control circuit for the polarized control relay including a front contact of said locking relay, a two-position relay at a remote point for controlling the polarity of the current supplied to said circuit, manually operable means for reversing said two-position relay, and means for preventing the reversal of said two-position relay unless said manually operable means is actuated when said control circuit is closed.

3. In combination with a railway track switch, a polarized control relay for the switch, a locking contact closed at times to indicate that traffic conditions are favorable for operating the switch, a control circuit for said relay including said locking contact, a two-position relay at a remote point for controlling the polarity of the current supplied to said circuit, a repeating relay at said remote point included in said circuit and energized only when said locking contact is closed, and manually operable means effective only when said repeating relay is energized for operating said two-position relay.

4. In combination with a railway traffic governing device, a polarized control relay for the device, a locking relay, a control circuit for said relay including a front contact of said locking relay, a two-position relay at a remote point for controlling the polarity of the current supplied to said circuit, manually controllable means for operating said two-position relay, and means controlled in accordance with traffic conditions for at times preventing the operation of said two-position relay.

5. In a centralized traffic controlling system for railroads, a track switch, a polarized control relay for governing said switch, a two-position switch control lever, having normal and reverse contacts, a locking contact controlled by traffic conditions adjacent said switch and closed only when conditions are proper for the operation of the switch, a two-position contact mechanism having normal and reverse contacts, normal and reverse control circuits for said track switch each including corresponding contacts of said lever and said contact mechanism and each including said locking contact and the winding of said control relay, and a polarized repeating relay controlled by normal and reverse contacts of said lever and effective to move said contact mechanism into agreement with said lever only in re-

sponse to a change in the position of the lever occurring while said locking contact is closed.

6. In a centralized traffic controlling system for railroads, a track section, a track switch associated with said section, a control lever, a control circuit energized in accordance with the position of said lever, switch control means connected to said control circuit and responsive to the actuation of said lever for controlling the operation of said track switch, locking means responsive to the specific condition of said section for locking and unlocking said switch control means, indicating means associated with said lever and governed over said control circuit for indicating the locked and unlocked condition of said switch control means, control registering means governed by said indicating means for registering the particular control effectively applied to said control circuit by said lever, and means governed by said control registering means for maintaining said control circuit open when said switch control means is locked and until said control lever is actuated into correspondence with said control registering means when said switch control means is unlocked.

7. Apparatus for the control of a movable device comprising a storing relay responsive to momentary energization and a control member, each having two positions corresponding to two positions of the device, a locking device which at times assumes a distinctive position to indicate that conditions are favorable for the operation of the movable device, a control circuit for the storing relay closed momentarily only if the control member is moved to one position or the other

when the locking device occupies said distinctive position, said control circuit being effective when closed to energize the storing relay to a position corresponding to that to which the control member is moved, and a control relay for governing the movable device controlled in accordance with the position of said storing relay.

8. Apparatus for the control of a movable device comprising a storing relay responsive to momentary energization and a control member, each having two positions corresponding to two positions of the device, a locking contact closed at times to indicate that conditions are favorable for the operation of the device, means effective only if said member is moved to one position or the other when said locking contact is closed to cause the relay to move to a position corresponding to that to which the member is moved, and a control circuit for the device including corresponding contacts of the member and of said relay.

9. Apparatus for the control of a movable device comprising a storing relay responsive to momentary energization and a control member, each having two positions corresponding to two positions of the device, a locking contact, means effective only if the member is moved to one position or the other when said locking contact is closed to cause the relay to move to a position corresponding to that to which the member is moved, and a control circuit closed only when the member and said relay occupy corresponding positions for operating the device to a position corresponding to that of said member.

RONALD A. McCANN. 35.
